UNITED STATES PATENT OFFICE.

FRITZ NÄNNY, OF HERISAU, SWITZERLAND.

PROCESS AND DEVICE FOR REMOVING THE CONNECTING THREADS IN EMBROIDERED FABRICS.

Application filed August 29, 1921. Serial No. 496,431.

(GRANTED UNDER THE PROVISIONS OF THE ACT OF MARCH 3, 1921, 41 STAT. L., 1313.)

To all whom it may concern:

Be it known that I, FRITZ NÄNNY, a citizen of the Republic of Switzerland, residing at Herisau, Switzerland, have invented certain new and useful Improvements in a Process and Device for Removing the Connecting Threads in Embroidered Fabrics (for which I have filed applications in Switzerland June 8th, 1918, Patent No. 79,781; in Switzerland August 3d, 1918, Patent No. 83,240; in Switzerland March 12th, 1919, Patent No. 83,430; in Germany August 14th, 1919, Patent No. 325,877, and in Austria September 23d, 1919, application No. A. 15 3,422-19); and I do hereby declare the following to be a clear, full, and exact description of the invention, such as will enable others skilled in the art to which it appertains to make and use the same, reference being had on the accompanying drawings, and to letters or figures of reference marked thereon, which form a part of this specification.

This invention relates to improvements in a process and a device for removing connecting threads in embroidered fabrics.

The embroidery on fabrics usually comprises patterns which consist of a number of isolated figures and in the manufacture of a pattern the thread is carried from one figure to another so as to leave a number of connecting threads passing over the intervening spaces. These connecting threads have to be removed.

In the process according to the present invention the embroidered fabric provided with the connecting threads is treated with means for causing said threads to be raised from the fabric and thereafter the fabric is singed for burning off the connecting threads, whereby the velocity of the moving fabric and the size of the singeing flame must be chosen so that the burning takes place partially whereupon the glowing parts of the connecting threads are extinguished. The device for carrying out the aforementioned process is characterized by at least one group each of the following means which are mentioned in the order in which they are arranged: means for raising the

connecting threads, means for burning or singeing said threads and means for extinguishing the burning threads.

The connecting threads can be cut or severed first by special cutting machines or by hand and then the fabric can be treated according to the afore-mentioned process for removing the connecting threads or preferably the severing as well as the removing of the connecting thread is effected by the above mentioned process.

Several constructional examples for carrying out the process according to the invention are illustrated on the accompanying drawings, in which:

Fig. 1 is a cross-section through a first constructional example of the device.

Fig. 2 shows a second form of the device in cross-section.

Fig. 3 illustrates a third constructional example of the device.

Figs. 4 and 5 show details.

Referring now to Fig. 1, 1 denotes the embroidered fabric which is moved over the guide rollers 2 and 3 to a rotary brush 5 provided with very hard bristles which brush is adapted to be adjusted by means of a hand wheel 4 in the direction towards and away from a roller 6 serving to hold the fabric in position and below which a guard plate 7 is provided. 8 denotes the supply pipe for combustible gas which is distributed by means of the conduits 9, 10 and 11 to the various rows 12 and 13 of burners. 14, 33, 37 and 36 are guide rollers and 15 is an adjustable brush which acts on the fabric stretched between the rollers 36 and 37. 17 and 18 are guide rollers. 19 denote a fire extinguishing or quenching means, which for instance may consist of a water spraying apparatus or a steam nozzle. 20 and 21 are squeezing rollers pressed together by a weight 21', 22 and 23 are guide rollers by means of which the fabric is guided over smoothing organs 24, i. e. curved surfaces 95 clad with wood, to which organs or surfaces the fabric is pressed by means of rollers 25 which act by their own weight. Finally the fabric passes between feed rollers 26, 27 to a device adapted to fold up the fabric 100

leaving the machine. This device consists of a pivotally mounted lever arm 28 to the end of which two rollers 50 and 51 are fixed between which the fabric is caused to pass. The lever arm 28 is swung to and fro by means of a crank disc 52 and a connecting rod 53.

The drive of the machine is effected from a counter-shaft 54 to which pulleys 55 are fitted, from which a belt or cord 56 actuates the rotating brush 15, another cord 57 imparts rotation to the brush 5 and a further cord 58 actuates the feed rollers 26, 27 while a further flexible member 59 imparts rotation to the crank disc 52. 29, 30 and 31 designate guard plates and 32 denotes a trough.

The operation of the above described device is as follows: The rotating brush 5 causes the connecting threads which in this case it is assumed are severed previous to the fabric being subjected to the process of removing said threads and which lie loosely on one side of the fabric to be raised and the threads are burned or singed by the two rows of burners 12 whereupon the severed connecting threads that are on the other side of the fabric are raised by the rotating brush 15 and singed by the rows of burners 13. As the connecting threads are sometimes of a certain length the whole length of these threads is not completely burned off by the aforementioned operation but only their outer points are singed and the glowing parts of the threads are then extinguished by the extinguishing means 19. Thus the burning of said threads occurs in steps. The glowing connecting threads singed by the rows of burners 12 and thereafter pressed to the fabric by the roller 16 cannot cause any damage to the fabric during the short time which the fabric moving at a high speed requires to pass from the roller 16 to the extinguishing means 19. The squeezing rollers 20, 21 which are always moist on account of the moist fabric passing between them cause the complete extinguishing of the parts of the connecting threads which may still be glowing and press the moisture out of the fabric which moisture collects in the trough 32. Upon a second passage of the fabric through the device the charred parts of the connecting threads are brushed off the fabric by the action of the brush 15, whereupon further parts of the connecting threads are burned off until the whole connecting threads are removed by a repeated treatment.

It is evident that the device could also be modified in such a way that several groups each consisting of means for raising the connecting threads, of a burner row and of extinguishing means are arranged in series. Instead of the rotating brush (or in addition to said brush) an air jet may be used for raising the connecting thread. To this end

an air conduit 38 is provided extending in a direction perpendicular to the direction in which the fabric moves which conduit is provided with a row of nozzles 39 extending approximately over the whole width of the fabric and through which nozzle either compressed air is forced against the fabric or air is sucked in.

In the embodiment of the invention illustrated in Fig. 2, 3 denotes the guide roller over which the fabric passes to the brush 5 by which the connecting threads of one side of the fabric are raised or by which brush, when the fabric passes a second time the device the singed parts of the connecting threads which have been burned during a previous passage of the fabric through the device are brushed off, thereupon the fabric reaches the rows of burners 12. At some little distance from the brush 5 an air conduit 34 is provided extending over the whole width of the fabric, to which conduit a continuous row of nozzles 35 is fixed, the nozzles ending near the fabric. Each nozzle opening has the shape of a narrow gap the longitudinal direction of which extends perpendicularly to the direction of movement of the fabric and the total length of said gaps corresponds approximately to the width of the fabric.

After the fabric has passed the rows of burners 12, it is lead to the brush 15 by which the other side of the fabric is acted upon in the same manner as the brush 5 has acted on the one side of the fabric. The arrangement of the guide rollers 33, 36 and 37 is similar to that shown in Fig. 1.

Below the brush 15 an air conduit 38 fitted with nozzles 39 of the same type as the air conduit 30 and the nozzles 35 is provided. The fabric moves then past the rows of burners 13 and to the extinguishing means 19.

If compressed air be projected through the nozzles 35 and 39 towards the fabric the effect is attained that at a certain force of the air jet the severed or already partly singed connecting threads are raised more or less, so that they are separated from the fabric and may be acted upon by the flame of the burners.

If a suction action is carried out by the nozzles a raising of the connecting threads is also effected.

Instead of treating fabrics with which the connecting threads have already been severed by a special cutting machine or by hand and to remove the cut connecting threads on the device according to the invention by singeing or burning the severing of the connecting threads may advantageously be effected during the same operation by which the severed connecting threads are singed. The severing of the threads can be attained by raising the connecting threads which form loops in their raised position;

on passing the burner flames the loops are at some point at least so much singed that by a subsequent action of the brushes they can be severed if the severing has not already been caused by the flame.

Referring now to the constructional example illustrated in Fig. 3, 3 and 6 designate guide rollers by which the fabric 1 is caused to pass to the means for raising the connecting threads which means consist of a row of nozzles 35. The nozzles 35 are again connected to a conduit 34 extending across the whole width of the fabric 1. The openings of the nozzles may have the shape of a narrow gap extending along the effective length of the conduit 34 as is shown in detail in Fig. 4 or separate nozzles 48 may be provided close to each other along the conduit 34. Plate strips 40 are soldered to the conduit 34, the free ends of said strips being bent and projecting beyond the gap of the nozzles.

The conduit 34 is connected to an exhaust fan not shown in the drawing. At a certain strength of the air current induced by the suction action the connecting threads are raised and form loops. The bent ends 41 of the severing fingers or strips prevent the fabric from being sucked towards the nozzles and from bulging. At a little distance from the row of nozzles the row of burners 12 is arranged through the flames of which the raised connecting threads are moved whereby they are singed at some spot. By means of a further row of nozzles 35 and a second row of burners 12 the same treatment is repeated whereby the loops of the connecting threads which have not been singed by the first treatment are now singed while the threads already severed are partly burned off. The rotating brush 42 is intended to sever the loops formed by the connecting threads which are singed but not severed, so that the free ends of said threads may be burned off upon subsequent passages. In this way the cutting or severing of the connecting threads is effected at the same time as the burning of the severed connecting threads.

After the fabric has passed (as in Figs. 1 and 2) the guide rollers 33, 36 and 37, on which passage the outer side of the fabric is acted upon by the rotating brush 15, said side of the fabric is subjected to the action of burners 13 which singe the loop formed by the connecting threads and the severed parts of the connecting threads. The row of air nozzles 43 and the second row of burners 13 act in a similar manner on this other side of the fabric as to the row of nozzles 35 and the second row of burners 12 acts upon the first side of the fabric.

I claim:

1. A process for removing the connecting threads from embroidered fabrics, which

comprises stretching the embroidered fabric between supporting means, raising the connecting threads while so supported, maintaining the threads so raised while between said supporting means and burning the raised threads.

2. A process for removing the connecting threads from embroidered fabrics, which comprises passing the fabric in stretched condition between spaced supports, raising the connecting threads from the fabric and then burning the raised threads while the fabric is maintained stretched between the supports.

3. A process for removing the connecting threads from embroidered fabrics, which comprises passing the fabric substantially horizontally, while stretched, between spaced supports, raising the connecting threads and burning them while the fabric is maintained stretched between said supports.

4. A process for removing the connecting threads from embroidery, which comprises passing the fabric substantially horizontally, while stretched, between spaced supports, and while the fabric is under tension raising the threads from the under surface of the fabric by suction and simultaneously drawing the fabric down to a flame to burn said threads.

5. A process for removing the connecting threads from embroidered fabrics, which comprises stretching the embroidered fabric between supporting means, raising the connecting threads while so supported, maintaining the threads so raised while between said supporting means, burning the raised threads, and extinguishing the ignited threads.

6. A process for removing the connecting threads from embroidered fabrics, which comprises stretching the embroidered fabric between supporting means, and while so stretched raising the connecting threads on one side of the fabric and burning them, then reversing the fabric and similarly raising and burning the connecting threads on the other side, and then quenching the burning threads.

7. A process for removing the connecting threads from embroidered fabrics, which comprises passing the fabric horizontally in stretched condition between spaced supports, and while so supported raising the threads from the fabric and burning them, reversing the fabric and similarly raising and burning the threads on the opposite side of the fabric, and then passing a quenching fluid through the fabric.

8. A process for removing the connecting threads from embroidered fabrics, which comprises stretching the embroidered fabric between supporting means, severing and raising the connecting threads while so sup-

ported, maintaining the threads so raised while between said supporting means and burning the raised threads.

9. A process for removing the connecting threads from embroidered fabrics, which comprises passing the fabric substantially horizontally in stretched condition between spaced supports, and while travelling, so supported, severing the threads, raising the threads by suction, burning the raised threads, reversing the fabric and similarly severing and burning the connecting threads on the opposite side, then passing a quenching medium through the fabric, and finally squeezing the quenching medium from the fabric.

10. A machine for removing the connecting threads from embroidered fabrics, comprising means adapted to raise the connecting threads from the fabric ground, means for singeing the raised threads, means for extinguishing the glowing parts of the singed threads, and means for moving the fabric past the afore-mentioned means at such a speed that the burning of the threads occurs in steps.

11. A machine for removing the connecting threads from embroidered fabrics, comprising means adapted to raise the connecting threads from the fabric ground, means for singeing the raised threads, means for extinguishing the glowing parts of the singed threads, means adapted to perform a rubbing action on the surfaces of the

fabric for severing singed connecting threads, and means for moving the fabric past said aforementioned means at such a speed that the burning of the threads occurs in steps.

12. A machine for removing the connecting threads from embroidered fabrics, comprising spaced guide rolls over which the fabric is passed in stretched condition, means between the rolls for first raising the threads from the fabric, and means between said rolls for then burning the raised threads.

13. A machine for removing the connecting threads from embroidered fabrics, comprising spaced guide rolls over which the fabric is passed, thread raising means between said rolls, igniting burners also between said rolls and arranged past said thread raising means, and quenching means to quench the ignited threads.

14. A machine for removing the connecting threads from embroidered fabrics, comprising spaced guide rolls over which the fabric is passed in stretched condition, severing fingers arranged between said rolls, suction means arranged to draw the severed threads from the fabric, and burning means to burn the raised threads, said suction means slightly deflecting the fabric from its line of travel.

In testimony whereof, I have signed my name to this specification.

FRITZ NANNY.
